UNITED STATES PATENT OFFICE.

RONALD F. McFEELY, OF BEVERLY, MASSACHUSETTS, ASSIGNOR TO UNITED SHOE MACHINERY COMPANY, OF PATERSON, NEW JERSEY, A CORPORATION OF NEW JERSEY.

PULLING-OVER MACHINE.

1,145,381.

Specification of Letters Patent. Patented July 6, 1915.

Application filed August 13, 1910, Serial No. 577,054. Renewed October 14, 1914. Serial No. 866,732.

To all whom it may concern:

Be it known that I, RONALD F. McFEELY, a citizen of the United States, residing at Beverly, in the county of Essex and State of Massachusetts, have invented certain Improvements in Pulling-Over Machines, of which the following description, in connection with the accompanying drawings, is a specification, like reference characters on the drawings indicating like parts in the several figures.

This invention relates to pulling-over machines and particularly to gripper actuating mechanism therefor and it has for an important object to modify the gripper movements to give to the drafting and stretching of the upper novel characteristics which are desirable under certain conditions.

The invention is herein shown as embodied in a machine which is of the type illustrated in prior United States Letters Patent No. 1,029,387, granted June 11, 1912, on my application, and is equipped with the improvements shown in my application Serial No. 539,413. In accordance with one feature of the invention, means is provided for adjusting simultaneously the length of the upper pulling movements of the several grippers. As explained in said earlier application the grippers are arranged to have an initial upper straightening movement and thereafter a power driven upper stretching movement.

In accordance with an important feature of this invention, provision is made for imparting to a gripper a predetermined extent of, or a measured, upper stretching movement. As I am advised, it is new by this invention to give to an upper a measured length of stretching as distinguished from stretching an upper by a predetermined tension as heretofore proposed. By pulling over accurately cut uppers by a measured stretching movement a uniformity in the manufacture of shoes can be obtained which will reduce the manual work involved and lessen the skill required in the several shoemaking operations and will tend to give to the product a uniformity approaching that obtained in the manufacture of articles of such material as cloth, paper, metal, etc. The realization of this object is greatly facilitated by initially straight-

ening the upper and drawing it down to the last before the measured stretching of the upper is commenced. When this procedure is followed a certain pattern of upper will pull over the last for which it is designed in substantially the same way and produce in all instances an identical shoe having the important lines such as the tip seam and the throat alike in each shoe. To facilitate this result provision may also advantageously be made for seizing the upper correctly and uniformly, as by gripping a predetermined distance from the edge of the upper, and in a predetermined relation to the tip line as explained in my prior United States Letters Patent No. 1,030,264.

In accordance with another feature of this invention, provision is made for adjusting simultaneously for a plurality of grippers, and preferably for all of the grippers of the machine, the length of upper stretching movement, although it may be not identically for different grippers and may even be oppositely for opposite side grippers. This provision for adjustment enables an operator to adapt the operation of this machine readily to the work or style of shoe in hand as he changes for example from a case of children's to one of misses' or ladies'. Provision will also preferably be made for adjusting the upper stretching movement of the toe and side grippers independently. By this means the extent of the longitudinal stretch effected by the toe gripper can be predeterminedly varied with relation to the extent of transverse stretching of the upper by the side grippers. This permits accommodation to patterns of upper which are not cut in the right proportion of length to width and require more or less stretching in one of the directions to make them fit the last over which the shoe is being made. As I am advised, to vary predeterminedly the relative extent of lengthwise and transverse stretching that will be effected by the machine with or without provision for measuring the stretch is a broadly new invention.

A feature of this invention of practical importance is found in novel arrangements for effecting forward drafting of the upper along the sides of the shoe. In accordance with the preferred embodiment of this in-

vention, as heretofore explained, the upper is seized and straightened and drawn up tightly to the last as an initial operation before the power driving mechanism is started. This allows inspection of the shoe and any required adjustments to be made while the upper is held under light tension and while there is insufficient friction between the last and the upper materials to produce objectionable distortion of the upper during adjustment. The adjustment usually considered of most importance is that for straightening the tip seam, although the frequency and the extent of this adjustment is greatly reduced by the provisions, described in said Patent No. 1,030,264, of tip seam position indicating means to guide the workman in correctly positioning the upper in the side grippers before they are closed. In accordance with this feature of the invention the upper positioning adjustments are made before the forward drafting of the upper as well as before the upper stretching operation. An advantageous construction embodying this feature of the invention is also herein employed in which the tip straightening mechanism is arranged for bodily movement longitudinally of the shoe by or with the drafting means. This arrangement insures that no loss of tip straightening adjustment shall occur in the drafting and the upper stretching operations and that these operations, by which the upper is put under tension about the last, shall be made with the upper in correct relation to the last. This provides uniformity in drafting and stretching the entire upper, giving the upper a permanent "set" in the shoe, instead of setting up local strains which tend to react and distort the upper when the last has been removed from the shoe.

It is desirable that the shoe be supported by the usual heel rest to steady it during the upper adjusting movements and in accordance with a further feature of this invention means is provided for bringing the heel rest into shoe supporting position before the power driven actuating mechanisms are started. Preferably and as herein shown, the heel rest is advanced to operative position as a part of the preliminary operation in which the side grippers are closed and caused to straighten the upper. Conveniently the machine will be equipped with a spring which will be put under tension during the automatic movement of the rest backwardly to shoe-receiving position and which will be released by the gripper controlling treadle to impel the rest forwardly. The heel rest is mounted to adjust itself laterally to the lateral position of the heel end of the last and when the power actuating mechanism is operated the rest is locked in its advanced position and is also locked in its laterally adjusted position in suitable

time to hold the shoe firmly for the upper fastening operation. The present invention contemplates an initial yielding advance of the rest without such locking thereof as will preclude convenient adjustment of the rest, or of the rest and the heel end of the shoe together, laterally during the period allowed for inspection of the shoe and the adjustments of the lightly held upper, and may include the lateral adjustment of the heel end of the last to position the forepart of the last symmetrically or otherwise as may be required for the pulling-over operation.

These and other features of this invention, including certain details of construction and combinations of parts will be explained in connection with the following description of the preferred embodiment of the invention and will then be pointed out in the claims.

Figure 1 of the drawings is a side elevation of a machine equipped with this invention; Fig. 2 is a front view of the updraw measuring mechanism; Fig. 3 is a plan view of the grippers operating mechanism; Fig. 4 is a perspective view illustrating the new mechanism; and Fig. 5 is a plan view.

The machine as a whole will be sufficiently described for the purpose of this specification by explaining that it comprises a shoe bottom rest 2, and preferably also a heel rest 4, with grippers 5 arranged to engage the upper at the toe end and at opposite sides of the ball of the shoe. The grippers are suspended by bars 6 from levers, the handled front sections 10 of which are preferably constructed and arranged for initial upward movement independently of the rear sections 12 as and for the purpose explained in my co-pending application Serial No. 539,413. The lever sections are fulcrumed on a rod 14 and at the rear ends are connected by rods 15 through springs 16 for operation by cams 17 and 18. A wedge block 19 for each gripper is connected to a hand lever 20 for adjustment to change simultaneously the tension of all the springs 16 and thereby increase or diminish the pulling force with which the grippers are uplifted to stretch the upper. The grippers are lowered to their shoe receiving position at the end of each operation and the jaws are simultaneously forced open, this being effected by the engagement of shoulders 22 on the gripper carriers 23 with the frame while the gripper bars 6 continue their descent. During this continued descent of bars 6 appropriate jaw closing springs, not shown, are put under compression which close the jaws upon the upper when reverse relative movement of bars 6 and carriers 23 is permitted. This relative movement is herein permitted by releasing the front arms 10 from their operative connection with the cam controlled rear arms 12, this connection being made through sliding latches 25, Fig.

1, which are carried by the arms 12 and engage suitable apertures in the front arms 10. The latches are connected to a foot treadle 26 by which they may be retracted prior to 5 the power operation of the machine to allow the grippers to seize the upper. The toe gripper latch may be withdrawn independently of the side gripper latches, if desired, by the push bar 27. Springs 28 are arranged as shown in Fig. 1 between the front 10 and rear arms of the levers 10, 12 for the purpose of lightly uplifting the grippers after they have seized the upper and before the power operation begins. This procedure 15 straightens the upper and affords opportunity for the workman to examine the shoe and to adjust the toe tip if necessary while the upper is held under light tension and thus provides that the shoe shall be finally 20 pulled with the upper in the desired adjusted position on the last so that ordinarily no adjustment of the tensioned upper is required. When the machine is started the rear lever arms 12 are moved alone until their front 25 ends pick up the front arms after which both arms are actuated together to stretch the upper. The machine may or may not stop with the upper under tension to permit further inspection of the shoe before the upper 30 is carried inwardly over the edge of the innersole to be fastened at the sides of the shoe by the tackers or otherwise. Further details of the machine may be found in said prior patents. The machine is also herein 35 shown as equipped with a mechanism for manual operation to last the toe portion of the shoe after the upper has been pulled over and while the shoe remains in the machine. This mechanism comprises end 40 embracing wipers mounted for advancing and closing movement by a lever 31 in a carrier 32 which in turn is arranged for up and down movement by a lever 34 in a bracket 35. A full description of this mechanism 45 may be found in the printed British specification No. 17091/09 and it need not be here further described inasmuch as its particular construction is not a part of the present invention.

50 In the illustrated machine embodying this invention the rod 40 which is operated by the treadle 26 to occasion the closing of the grippers and their light uplift for straightening or, according to the strength of spring 55 28, initially stretching the upper, has a collar 411 vertically adjustable thereon which lifts a latch 42 by which the heel rest is locked in its retracted position to which it is moved by the power mechanism through 60 the cam slide 86 at the end of the preceding cycle against the tension of spring 44. This spring acts through rack rod 41, toothed shaft 43 and toothed supporting slides 45 to cause a yielding advance of the heel rest 65 into shoe supporting position where it sus-

tails the shoe against loose movement while any required upper adjustments are being made.

The heel rest, which has forwardly and outwardly inclined sides, is supported for 70 lateral swinging movement to adapt itself to the lateral position in which it finds the shoe. The rest is also mounted on a transverse pivot 50 and is held by springs 52 forward away from a locking bar 54 until 75 it meets the shoe when the pressure of the heavier spring 44 causes engagement of the locking bar with the rest to restrain lateral displacement of the heel end of the shoe in the upper adjusting operation. The pressure of the spring 44 is, however, insufficient to interfere with any lateral adjustment of the heel end of the last which the operator may desire to make for the purpose of positioning the forepart of the shoe 85 laterally into symmetrical or other desired relation to the pulling-over and the lasting devices which operate directly upon the forepart only of the shoe. A yoke 60 rests upon the side gripper levers 10 as in Figs. 90 1 and 2 and is lifted by them as they rise, and during the initial, upper straightening movement of the grippers the rise of the yoke acts through an arm 62 to turn a rock shaft 63 on which is a second segmentally 95 toothed arm 64 that engages with a toothed portion of a slide 65 movable transversely of the machine in guideways in the frame. The slide has inclined tongue and groove connection with the frame so that it is lifted 100 as it is moved endwise. The slide 65 is thus adjusted upwardly by and in proportion to the extent of the initial movement of the grippers. This slide is arranged over stops 68 that project upwardly from the gripper 105 lever arms 10. The slide 65 has on its rear face a ratchet toothed area, shown at the right in Fig. 2, with which an endwise movable pawl 70 engages. This pawl rod, seen in Fig. 1, is held normally away from the 110 ratchet face by a spring 72 which also holds the rear end of the rod against a wedge pin 74 which is guided vertically in the upper arm 10 of an updraw lever and is held down upon the arm 12 thereof by the spring 76. 115 The pawl rod locks the slide 65 from further movement and holds it stationary as an abutment for the stops 68. The continued movement of the yoke 60 is taken up by a relief spring 61 which is located between the 120 loose rock shaft arm 62 and a rigid abutment on the rock-shaft, as appears in Fig. 2. When the stops 68 reach the abutment slide 65 in the power driven upper stretching movement of levers 10, 12, then the 125 springs 16 yield to allow the cams 17, 18 to complete their stroke. This arrangement provides that the abutment slide 65 shall be raised by, and proportionally to, the initial uplift of the gripper levers during which 130

the upper is being straightened up and drawn to the last, and that it shall become locked during the power updraw that is effected by the lever arms 12. The slide 65 thus becomes an updraw limiting abutment which is automatically set during each initial upper straightening movement to provide for a predetermined length of upper stretching movement. It is to be noted that the length of upper stretching movement is not affected by the length of the upper straightening movement for if the upper straightening movement carries the lever arms 10 farther up at one time than at another the abutment 65 is automatically adjusted correspondingly higher.

As I am advised, it has not heretofore been attempted to provide, in a machine that has a divided movement of a lever or the like, the first portion of which movement is variable according to the condition of the work or otherwise, means for predetermining the length of the second portion of the movement regardless of the length of the first portion. This feature of the invention will be found to be of value in other relations than that herein shown and it is intended by this patent to protect it wherever it may be used. In the present use, a constant, predetermined, or measured length or extent of upper stretching is obtained unaffected by variations in the length of the upper straightening portion of the stroke of lever arms 10, 12, which latter portion of the lever movement may vary with differences in the size of uppers and also with differences in the length of upper that may be inserted into the gripper jaws. The advantages of a measured extent of upper stretching have been herein sufficiently suggested to insure that the merits of this improvement will be appreciated. The yoke 60 is preferably swiveled on the arm 62 so that one side gripper lever may rise higher than the other as may be required in the well-known operation of the machine. By reason of this mounting the yoke serves as an equalizer set by the two side grippers. The yoke is preferably connected to the arm 62 by an eccentric 82 which can be manipulated to vary the vertical relation of the ends of the yoke arms to the abutment slide 65 for increasing or decreasing the measured length of upper stretching movement for all the grippers simultaneously. The screw threaded connection of the stops 68 to the lever arms 12 provides for relatively varying the length of longitudinal and transverse upper stretching effected by the toe and side grippers.

The cam shaft 85 of the machine has a cam roll that is grooved to receive a roll on a slide 86, Figs. 1 and 4, and this slide has an upright arm from which is forwardly projected a rod 88 which is encircled by a

spring 89 and passes through a block 90 adjustably mounted on a hand lever 91 of a rock-shaft 92. The rock-shaft has toothed sections which engage rack teeth on blocks 94, with which the side grippers have connection, whereby both side grippers are moved forwardly from the cam shaft during each power actuated stretching movement of the grippers. The blocks 94 have bearings for the usual tip straightening hand lever shaft 96 of said Patent No. 1,029,387 which, through pinions and reversely arranged racks 97 connected to the gripper carriers 23, Fig. 4, is employed for moving the side grippers in opposite directions lengthwise of the shoe, one forwardly and the other backwardly, for shifting the upper longitudinally around the last. The adjustable connection of the block 90 with the rock-shaft arm 91, see Figs. 4 and 5, provides for obtaining different degrees of forward drafting of the upper by the side grippers after the initial upper positioning adjustments have all been made. This gives a drafting of the adjusted upper as contrasted with a drafting of the upper prior to its correct positioning on the last.

In the use of the machine, the operator presents in the usual way an assembled shoe, the heel portion of which may or may not have been lasted. The toe gripper may be first released and caused to straighten the upper longitudinally by disengaging its latch 25 by the push rod 27 as explained in my application Serial No. 539,413, or the toe gripper and the side grippers which straighten the upper transversely about the last may be released together by the foot treadle 26. The same movement of the treadle releases the heel rest, if the described arrangement for that purpose is employed, and allows it to be yieldingly advanced. The heel rest adjusts itself automatically to the longitudinal position of the shoe and by reason of its inclined sides also to the transverse or lateral position in which it finds the heel and then is tipped lightly back against the ratchet plate 54. If the operator discovers, during the inspection which is now permitted, that the last requires to be shifted in order to present the shoe symmetrically to the pulling over or the toe lasting mechanisms, the rest can be easily pressed laterally to one side or the other of the machine to effect such adjustment of the last relatively to the mechanisms which operate on the forepart of the shoe. The heel rest serves to hold or steady the last during the adjustments of the upper by the grippers which may be found to be necessary, including the tip straightening adjustment. During the initial uplifting of the grippers the levers 10 have raised the yoke 60 and adjusted the abutment stop 65 through the described mechanism. When the machine is

next started by depressing the usual power shaft controlling treadle the rear arms 12 of the levers act through the wedge plunger 74 to thrust the rod 70 forward against the ratchet faced portion of the abutment slide 65 and thereby lock it in position to arrest the final updrawing or the upper stretching movement at a point which is located a measured distance from the point where the upper stretching movement, as distinguished from the initial upper straightening movement, began. This measured distance, which is predetermined for the grippers individually by the stops 68 and for the series of grippers as a whole by the adjustment of the eccentric 82, is the portion of the stroke of the lever sections 12 after they pick up the lever sections 10, as by reengagement of the latches 25 with arms 10. The spring 61 yields to permit continued rise of the yoke 60 and the springs 16 yield to permit completion of the stroke of cams 17, 18. During this power stretching of the upper the cam slide 86 is actuated to advance the spring plunger 88 and effect foredraw of the previously adjusted upper. The customary stopping of the machine while the upper is held under final tension may be omitted if desired and the upper fastening operation effected at once or the toe portion of the shoe may be lasted as described in said British specification.

The described foredrawing of the upper is advantageous as a preparation for the toe lasting operation because the forward pulling strain applied to the upper by the side grippers tends to offset the effect on the upper at the sides of the toe produced by the backward component of the rubbing action of the usual toe embracing wipers as they close and move endwise over the toe.

Having explained the nature of this invention and described by way of exemplification a preferred construction embodying the same, I make the following claims which I intend shall be construed and interpreted to cover all the patentable novelty of which this invention is possessed and for which I am entitled to protection under the statutes, whether or not every feature of the invention has been particularly pointed out elsewhere in this specification.

I claim—

1. A pulling-over machine, having in combination, means for resting a last, grippers for seizing an upper at the toe end and at opposite sides of the shoe, and power means to actuate a gripper to pull the upper a measured distance.

2. A pulling-over machine, having in combination, means for resting a last, grippers for seizing an upper at the toe end and at opposite sides of the shoe, and means to actuate the grippers to pull the upper a measured distance, said machine having pro-

vision for simultaneously adjusting the limit of the pulling movement for a plurality of the grippers.

3. A pulling-over machine, having in combination, means for resting a last, grippers 70 for seizing an upper at the toe end and at opposite sides of the shoe, and means to actuate the grippers to pull the upper a measured distance, and a limiting stop common to all the grippers and separately adjustable stops carried by the toe and side grippers coöperating with said common stop.

4. A pulling-over machine, having in combination, means to rest a shoe, means for seizing the upper and actuating mechanism constructed and arranged to effect straightening of the upper about the last under a tension less than the final tension and then to effect a measured length of upper pulling 85 movement.

5. A pulling-over machine, having in combination, means to rest a shoe, means for seizing the upper and actuating mechanism constructed and arranged to effect an initial 90 pulling of the upper and then automatically to effect a predetermined length of upper pulling movement.

6. A pulling-over machine, having in combination, means to rest a shoe, means for 95 seizing the upper, and operating mechanism by which to effect initial pulling of the upper about the last and adjustment into desired relation to the last, and thereafter to effect a measured length of upper stretching 100 movement.

7. A pulling-over machine, having in combination, means to rest a shoe, means for seizing the upper, means to straighten it under a predetermined tension, and means 105 for thereafter pulling the straightened upper through a predetermined distance.

8. A pulling-over machine, having in combination, means to rest a shoe, means for seizing the upper, and mechanism first to 110 apply a predetermined tension to an upper and then to stretch the tensioned upper a measured distance.

9. A pulling-over machine, having in combination, means to rest a shoe, means for 115 seizing the upper, and mechanism first to apply a predetermined tension to an upper and then to stretch the tensioned upper a measured distance, said machine having provision for adjustment to vary the length of said last mentioned stretching movement independently of the initial tension applied to the upper.

10. A pulling-over machine, having in combination, means to rest a shoe, means 125 for seizing the upper, and mechanism first to apply a predetermined tension to an upper and then to stretch the tensioned upper a measured distance, said machine comprising longitudinally stretching means and 130

transverse stretching means and having provision for varying the relative lengths of stretching movement effected by said two means.

5 11. A pulling-over machine, having in combination, means to rest a shoe, means for seizing the upper, and mechanism first to apply a predetermined tension to the upper and then to stretch the tensioned upper a measured distance lengthwise and transversely of the shoe and having provision for varying the relative lengths of such stretching movements.

10 12. A pulling-over machine, having in combination, means to rest a shoe, means for seizing the upper at the toe and sides of the shoe, and mechanism first to apply a predetermined tension to the upper and then to stretch the tensioned upper a measured distance, said machine having provision for adjustment to vary the said measured distance simultaneously for the toe and side pulling means.

15 13. A pulling-over machine, having in combination, means to rest a shoe, means for seizing the upper at the toe and sides of the shoe, and mechanism first to apply a predetermined tension to the upper and then to stretch the tensioned upper a measured distance, said machine having provision for adjustment to vary the said measured distance relatively for the toe and the side pulling means.

20 14. A pulling-over machine, having in combination, means to rest a shoe, means for seizing the upper, and mechanism first to apply a predetermined tension to the upper and then to stretch the tensioned upper a measured distance, said machine having provision for varying such tension without altering the length of the final pull.

25 15. A pulling-over machine, having in combination, means to rest a shoe, means for seizing the upper, and mechanism first to apply a predetermined tension to the upper and then to stretch the tensioned upper a measured distance, said machine having provision for varying predeterminedly the length of the final pulling movement irrespective of the initial tension applied to the upper.

30 16. A machine of the class described, having in combination, a gripper and actuating means for moving the gripper in two steps in substantially the same direction, the length of the first step varying with the resistance offered by the work and the length of the second step being predetermined.

35 17. A machine of the class described, having in combination, a gripper and actuating means for moving the gripper in two steps in substantially the same direction, the first step being yieldingly effected and variable and the second step being substantially unyieldingly effected and invariable in length.

18. A machine of the class described, having in combination, a gripper and actuating means for moving the gripper in two steps in substantially the same direction, the first step being yieldingly effected and variable, and a stop which is set automatically during such first step to determine the limit of the second step.

70 19. A machine of the class described, having in combination, a gripper and actuating means for moving the gripper in two steps in substantially the same direction, the first step being yieldingly effected and variable, and a stop which is set automatically in position determined by the length of the first step to arrest the second movement of the gripper.

75 20. A machine of the class described, having in combination, a gripper and actuating means for moving the gripper including a spring to lift the gripper, and means to pick up the gripper at the point where the spring lifted it, and to move the gripper a predetermined further distance.

80 90 21. A machine of the class described, having in combination, a gripper and actuating means for moving the gripper including means to move the gripper a variable distance, a stop set in a position determined by said variable distance, and means for moving the gripper to a position determined by said stop.

85 95 100 22. A machine of the class described, having in combination, a gripper, means for yieldingly actuating the gripper, a stop moved proportionally to the movement of the gripper, and means for subsequently moving the gripper until it is arrested by the stop.

105 110 115 23. A machine of the class described, having in combination, a gripper, means for yieldingly actuating the gripper, a stop moved proportionally to the movement of the gripper, means for arresting the movement of the stop, and means for further actuating the gripper until it is arrested by the stop.

120 115 125 24. A machine of the class described, having in combination, a gripper, and actuating means, and a stop which is moved proportionally to the movement of the gripper during a portion of the gripper movement and is then arrested to limit the final movement of the gripper.

120 125 130 25. A machine of the class described, having in combination, a gripper and actuating means for uplifting the gripper, a stop arranged out of contact with the gripper and moved with it, and means for arresting the movement of the stop and then further moving the gripper to the stop.

125 130 26. A machine of the class described, having in combination, a gripper, means for lifting the gripper, the stop 65, the connection 60, 61, 62, 64 between the gripper and

the stop for moving the stop from the gripper, and means 70, 74, 12 for arresting the movement of the stop while the gripper moves to it.

5 27. A machine of the class described, having in combination, a gripper, means 28, 10 for lifting the gripper, the stop 65, connections from the gripper to the stop to effect displacement of the stop during such 70 lifting movement, means 17, 18, 12, 25, for further lifting the gripper, and means for locking the stop at the beginning of the second movement of the gripper.

15 28. A machine of the class described, having in combination, a gripper, means for lifting the gripper in two steps and means adjusted during the first step for limiting the length of the second step.

20 29. A machine of the class described, having in combination, a gripper, means for lifting the gripper a distance variably determined in each operation by the resistance of the stock, means for further lifting the gripper, and means adjusted during such variable movement to limit the further movement to a uniform length for successive 80 shoes.

30 30. A machine of the class described, having in combination, a gripper having an upper straightening movement and an upper stretching movement and a stop set automatically in position determined by the length of the straightening movement to arrest the stretching movement.

35 31. A machine of the class described, having in combination, a gripper having an upper straightening movement and an upper stretching movement, and means set automatically by the first movement to insure a second movement of uniform length for each shoe.

40 32. A pulling-over machine, having in combination, grippers to engage an upper at the toe end and opposite sides of the ball of a shoe, a stop 65 for limiting the upper stretching movement of all the grippers, and means controlled by initial movement of the side grippers for setting the stop.

45 33. A pulling-over machine, having in combination, grippers to engage an upper at the toe end and at opposite sides of the ball of a shoe, a stop 65 for limiting the upper stretching movement of all the grippers, and means including the pivoted yoke 110 controlled by the two side grippers and having the adjustable connection 82 with the stop for setting the stop automatically.

50 34. A pulling-over machine having in combination, grippers to engage an upper at the toe-end and opposite sides of the ball of a shoe, and operating means arranged to effect step by step updrawing of the upper including a measured final step.

55 35. A pulling-over machine, having in combination, grippers to engage an upper

at the toe end and opposite sides of the ball of a shoe, manually controlled means for effecting closing of the grippers and for releasing special springs which actuate the grippers to straighten up the upper, an up-draw limiting stop carried up with the grippers in said movement, and power driven means to actuate the grippers for stretching the upper through a distance limited by said stop.

75 36. A pulling-over machine, having in combination, grippers for engaging the upper and operating mechanism to actuate the grippers to straighten the upper preparatory to stretching it and thereafter to stretch 80 the upper a measured amount.

80 37. A pulling-over machine, having in combination, grippers for engaging the upper at the toe and at opposite sides of the shoe and operating mechanism to actuate 85 the grippers to stretch the upper a measured amount.

85 38. A pulling-over machine, having in combination, grippers for engaging the upper at the toe and at opposite sides of the shoe and operating mechanism to actuate 90 the grippers to stretch the upper a measured amount which can be varied at the toe and at the sides relatively.

90 39. A pulling-over machine, having in combination, grippers for engaging the upper, and mechanism controlled by an initial movement of the grippers for stretching the upper a measured amount which shall be uniform for successive shoes.

95 40. A pulling-over machine, having in combination, grippers for engaging the upper at the toe and at opposite sides of the shoe and operating mechanism to actuate the grippers to stretch the upper longitudinally and transversely including means positioned in accordance with movement of the side grippers for limiting the longitudinal stretching movement.

100 41. A pulling-over machine, having in combination, grippers for engaging the upper at the toe and at opposite sides of the shoe, operating mechanism for actuating the grippers in two steps, a stop for limiting the final step and setting means therefor including an equalizer set by the two side grippers and operatively connected with the stop.

105 42. A pulling-over machine, having in combination, devices for stretching the upper longitudinally and transversely of the shoe in the pulling-over operation, actuating mechanism therefor and means for predeterminedly measuring the length of the longitudinal stretching.

110 43. A pulling-over machine, having in combination, devices for stretching the upper, actuating means therefor, and means for predeterminedly measuring the length 120 of the longitudinal and transverse stretch.

ing movements and having provision for relatively varying the lengths of said two movements.

44. A pulling-over machine, having in combination, grippers to pull an upper, a rest to sustain the last, power operated means to actuate the grippers and the rest and to return them to inactive position, and manually controlled means for causing the grippers to seize and straighten the upper and for causing the heel rest to move into shoe sustaining position. 70

45. A pulling-over machine, having in combination, grippers which are movable to adjust the upper on the last, a heel rest that is movable to adapt itself to the position of the last, power operated mechanism for actuating the grippers and for actuating the rest including means for locking the rest, and means independent of the power operated means for causing the grippers to seize and straighten the upper and the heel rest to advance. 75

46. A pulling-over machine, having in combination, grippers, means for actuating the grippers to straighten the upper and hold it under light tension to permit adjustment of the upper on the last, a heel rest normally occupying a retracted position, and means for guiding, advancing and maintaining the rest in position to support the shoe for the upper adjusting operation. 80

47. A pulling-over machine, having in combination, grippers, means for actuating the grippers to straighten the upper and hold it under light tension to permit adjustment of the upper on the last, a heel rest normally occupying a retracted position, means for guiding, advancing and maintaining the rest in position to support the shoe for the upper adjusting operation, and means for further actuating the grippers and the heel rest for the pulling over operation. 100

48. A pulling-over machine, having in combination, grippers, a heel rest, means manually controlled to actuate the grippers and the heel rest to straighten the upper and to hold the upper and the last with the upper under tension for inspection and adjustment, and power driven means for locking the heel rest and further actuating the grippers. 110

49. A pulling-over machine, having in combination, grippers, a heel rest, means for initially actuating the heel rest and the grippers and causing them to hold the shoe for inspection, said parts being arranged to permit relative adjustment of the grippers and the rest, and means for further actuating said grippers and the rest to complete the pulling-over operation. 115

50. A pulling-over machine, having in combination, grippers, a heel rest normally occupying a retracted shoe receiving position, devices to release and advance the rest 120

against the shoe preliminary to the power operation of the machine whereby accurate positioning of the rest and shoe is permitted, and power operated means for actuating the rest and grippers to pull over the shoe. 70

51. In a pulling-over machine the combination with grippers and means for actuating them, of a heel rest, means adapted for manual operation before the grippers are operated to cause the heel rest to advance into operative engagement with the heel end of the shoe and permitting lateral positioning thereof, and power means to effect locking of the heel rest during the last portion of the pulling-over operation. 80

52. In a pulling-over machine the combination with grippers and means for actuating them, of a heel rest, means to retract the rest to shoe receiving position, a spring against which the rest is retracted, manual means for releasing the rest to permit its adjustment to the shoe, and means to lock the rest automatically in adjusted position for the upper pulling operation. 85

53. In a pulling-over machine, the combination with grippers and a heel rest, of treadle operated means for closing the grippers and advancing the heel rest to operative position. 90

54. In a pulling-over machine, the combination with grippers and a heel rest, of treadle operated means for effecting closing and initial uplifting of the grippers to straighten the upper and hold it under light tension to permit inspection and adjustment and to cause the heel rest to be advanced into position to hold the last during such adjustment. 100

55. A pulling-over machine, having in combination, pulling-over mechanism for working the upper over the fore part of a last, power operating mechanism therefor and a heel rest which normally stands away from the shoe, and means independent of the power mechanism for moving the rest forwardly into last resting position, said rest being mounted for lateral movement while in last resting position to adjust the last into symmetrical relation to the pulling-over mechanism. 110

56. A pulling-over machine, having in combination, operating means to straighten an upper over a last having provision for automatically pausing to permit inspection and adjustment of the work, and for thereafter foredrawing and updrawing the upper. 115

57. A pulling-over machine, having in combination, operating means to straighten an upper over a last having provision for automatically pausing to permit inspection and adjustment of the work and for thereafter effecting relative lengths of foredraw and updraw that are adjustable. 120

58. A pulling-over machine, having in 125

combination, operating means to straighten an upper over a last having provision for automatically pausing to permit inspection and adjustment of the work, and for there-
5 after effecting an adjustably predetermined length of upward stretching of the shoe stock and an independently variable length of foredraw.

59. A pulling-over machine, having in combination, grippers and operating mechanism to close the grippers for seizing the upper and to uplift them for initially pulling, the upper, and additional mechanism to move the grippers for then drafting the upper and stretching it a measured distance.

60. A pulling-over machine, having in combination, means for initially pulling an upper having provision for permitting adjustment of the upper while it is lightly held and then further stretching the upper a measured distance.

61. A pulling-over machine, having in combination, means for gripping an upper at the toe and opposite sides of the ball, means for adjusting the upper on the last, means for advancing the side grippers and the adjusting means to effect foredraw, and power driven means thereafter to actuate the grippers to effect updrawing of the previously adjusted and foredrawn upper.

62. A pulling-over machine, having in combination, means for gripping, adjusting and automatically stretching an upper, and means for automatically drafting the upper lengthwise after it is adjusted.

63. A pulling-over machine, having in combination, means for gripping, initially straightening and finally stretching an upper, and means for automatically actuating the grippers to draw the upper forwardly at the two sides of the shoe only after the initial straightening operation.

64. A pulling-over machine, having in combination, side grippers, tip straightening mechanism including a hand lever and oppositely arranged connections thereto for adjusting the side grippers in opposite directions, a second hand lever and connections to the grippers for adjusting them and the first lever together in the same direction.

65. A pulling-over machine, having in combination, side grippers, tip straightening mechanism therefor substantially as described, the toothed shaft 92 having connection with the grippers permitting independent movement of the grippers in the tip straightening operation, and the hand lever 91 for operating the shaft to effect forward or backward drafting of the upper at the two sides of the shoe.

66. In a machine of the class described, pulling-over grippers for engaging the upper at the sides of the shoe, actuating mechanism including means for effecting foredraw of the upper held by the side grippers, and

end lasting means including wipers movable inwardly over the shoe bottom and backwardly at the sides of the shoe in opposition to the direction of the foredraw strain on the upper.

67. In a machine of the class described, pulling-over side grippers and means for actuating them to strain the upper at the sides of the forepart of the shoe upwardly and forwardly, and lasting means acting inwardly upon the foredrawn upper at the sides of the shoe and having a component of backward movement which is offset by the previously effected foredraw.

68. In a machine of the class described, end lasting mechanism including wipers movable inwardly and backwardly over the forepart of the shoe, and pulling-over means to prepare the shoe for the lasting operation and including side grippers and actuating means for causing said grippers to strain the upper forwardly at the sides of the shoe in advance of the backwardly moving lasting means.

69. In a pulling-over machine, a gripper and an actuator having a divided movement the first portion of which is variable according to the condition of the work, and means for predetermined the length of the second portion of said movement.

70. In a pulling-over machine, a tool for operating upon the work and an actuator therefor having a divided movement, the first portion of which is determined by the work, and means for predetermined the length of the second portion of said movement independently of the length of the first portion.

71. In a pulling-over machine, means for resting the last, grippers for seizing the upper at the toe and opposite sides of the shoe, and means to actuate the grippers and the last relatively to stretch the upper a measured distance.

72. A pulling-over machine having, in combination, means to rest a last, means to seize the upper, means for yieldingly stretching the upper, and separate means for adjusting the tension and the length of the pulling movement.

73. A pulling-over machine having, in combination, means for resting a last, grippers for seizing an upper at the toe and opposite sides of the last, means for yieldingly actuating the grippers to stretch the upper, means for varying the tension of all of the grippers simultaneously, and means for varying the length of the pulling movement of all the grippers simultaneously.

74. A machine of the class described having, in combination, a gripper and actuating means for moving the gripper in two steps, the length of the first step varying with the resistance offered by the work and the length of the second step being predetermined.

75. A machine of the class described having, in combination, a tool for operating upon the work, and actuating means for moving the tool in two steps, the length of the first step varying with the resistance offered by the work and the length of the second step being predetermined.

76. A machine of the class described having, in combination, a tool for engaging the work, actuating means for moving the tool, including a spring for effecting initial movement of the tool, and automatic means to pick up and further move the tool a predetermined distance from the point at which the spring left it.

77. In a machine of the class described, the combination with grippers and a heel rest, of a treadle and connections for causing the operation of the grippers and the heel rest successively.

78. A machine of the class described having, in combination, a gripper and actuating means for moving the gripper including a spring through which the movement of the gripper is yieldingly effected to pull the upper and is made variable in length, and a stop adjustable to limit the length of the gripper movement to less than the pulling movement which the tension of the spring would normally give to the gripper.

79. A machine of the class described having, in combination, grippers arranged to engage the upper at opposite sides of the forepart of a shoe and actuating means for moving said grippers including springs through which the movement of the grippers is yieldingly effected to pull the upper and is made variable in length, and stops for the right and left side grippers which are relatively adjustable to arrest the yieldingly effected movement of the gripper acting on one side of the shoe while the gripper acting on the other side of the shoe is given a greater length of upper pulling movement.

80. A machine of the class described having, in combination, a gripper having one movement and then another movement imparted by yielding means permitting variation in length of the movement, and means set automatically by the first movement to insure a second movement of uniform length for each shoe.

81. A machine of the class described having, in combination, grippers arranged to engage the upper at opposite sides of the forepart of a shoe and actuating means for moving said grippers including springs through which the movement of the grippers is yieldingly effected to pull the upper and is made variable in length, and means

arranged for adjustment to cause the grippers to pull the upper farther on one side of the last than on the other side.

82. A machine of the class described having, in combination, grippers arranged to engage the upper at opposite sides of the forepart of a shoe and actuating means for moving said grippers including springs through which the movement of the grippers is yieldingly effected to pull the upper and is made variable in length, and pulling movement limiting means for the two side grippers which is arranged for adjustment to produce on a selected side of the last a shorter pulling movement than is produced on the other side of the last.

83. In a pulling-over machine, the combination with grippers and power operating mechanism for causing said grippers to pull over an upper, of a heel rest, means maintaining the heel rest in retracted position while the grippers receive the shoe, and manually controlled means for causing advance of the rest to the shoe and permitting adjustment thereof into desired lateral relation to the shoe prior to the actuation of the power operating mechanism for the grippers.

84. A pulling-over machine having, in combination, toe and side grippers, operating mechanism to effect upper pulling movements of said grippers, positively acting means for limiting the length of the upper pulling movement of the grippers, and means for adjusting said length of movement of the grippers independently one of another.

85. A pulling-over machine having, in combination, toe and side grippers, operating mechanism to effect upper pulling movements of said grippers respectively lengthwise and transversely of the last and means by which the extent of the lengthwise stretching of the upper by the toe gripper can be predeterminedly varied with relation to the extent of transverse stretching of the upper by the side grippers.

86. A lasting machine having, in combination, means for pulling an upper over a last, and means for automatically stopping the pulling movement at successive points in one cycle of the machine's operations, the second point having a predetermined relation to the first point.

In testimony whereof I have signed my name to this specification in the presence of two subscribing witnesses.

RONALD F. McFEELY.
